ATTACHING MEANS FOR CARBON PAPER
PACKS OR THE LIKE

Robert A. Kohut, New York, N. Y., assignor to
Queen Ribbon and Carbon Co., Inc., Brooklyn,
N. Y., a corporation of New York

Application June 11, 1949, Serial No. 98,505

2 Claims. (Cl. 282—19)

1

This invention relates generally to means for temporarily attaching a flexible sheet or paper packs to a support and has particular reference to means for attaching a carbon paper pack to the cross bar or blade of fanfold billing machines or manifold-type machines. The said means are also employable for attachment of sheets in connection with typewriters where continuous forms are used.

A carbon paper pack for use with a fanfold billing machine or manifold-type machine, comprises a plurality of sheets having their rear edges bound together by any suitable means, such as stitches, each of the sheets being folded back and forth to provide a number of layers of substantially equal length. These folded sheets are positioned in and secured by said stitches to a folder or binder which consists of a sheet of relatively heavy paper folded at its top providing a backing and a front flap for the plurality of carbon sheets. The folded top of the said sheet of relatively heavy sheet of paper is spaced from the top of the bound carbon sheets, thus providing a tubular slide for the aforementioned cross bar or blade.

It has been found that when the said cross bar or blade is inserted in said tubular slide portion of the folder or folded binder, because of the usual loose fit, the cross bar or blade inconveniently slides or moves relatively to the latter making complete adjustment or attachment of the carbon paper pack thereon uncertain thereby interfering with efficient operation of the machine.

It is, therefore, an object of the present invention to provide a carbon paper pack with means whereby the latter may be easily readily attached and detached from the usual cross bar or blade of the aforementioned machines.

It is another object of the present invention to provide a carbon paper pack or even a single sheet with means for temporarily affixing the same to a bar or other support.

A further object of the present invention is to provide a pack or a sheet with perforations and a pressure sensitive adhesive strip over the perforations whereby means are provided extendable through the perforations by hand pressure on the strip for removably attaching the pack or sheet to a flat member.

A still further object of the present invention is to provide the aforementioned flat member with the perforations and with the pressure sensitive adhesive strip for the purpose of removably attaching a pack or sheet to the flat member.

2

According to one phase of the invention, a carbon paper pack is provided with a jacket, folder or binder having a fold at the top of the pack constituting a flat tube or loop within which a bar or blade may be slipped; the said fold being provided with perforations over which an adhesive strip is secured. By applying a slight pressure to the said strip portions, the latter will enter the perforations and the adhesive coating on the said strip portion will adhere to the said blade or bar holding it in fixed position and against lateral movement within the said tube or loop portion of the binder.

Various further and more specific objects, features and advantages will clearly appear from the detailed description given below taken in connection with the accompanying drawing which forms a part of this specification and illustrates merely by way of example two embodiments of the device of the invention.

The invention consists in such novel features, arrangements and combinations of parts as may be shown and described in connection with the articles herein disclosed by way of example only and as illustrative of certain preferred embodiments.

In the drawings, Fig. 1 is a plan view of a carbon paper pack embodying the invention;

Fig. 2 is an end view thereof;

Fig. 3 is a sectional view taken through line 3—3 of Fig. 1;

Fig. 4 is a plan view of a sheet of material incorporating the invention;

Fig. 5 is a sectional view taken through line 5—5 of Fig. 4;

Fig. 6 is a fragmentary view showing an application of the invention in a modified form; and

Fig. 7 is a sectional view taken through line 7—7 of Fig. 6.

In the following description and in the claims, parts will be identified by specific names for convenience, but such names are intended to be as generic in their application to similar parts as the art will permit. Like reference characters denote like parts in the several figures of the drawing.

Referring now to the drawing, there is disclosed a carbon paper pack 10 comprising a plurality of folded sheets of carbon paper 12. Folded over the top of said plurality of sheets 12 is a flexible sheet 11 of any suitable material, the fold line 11a of the folded sheet 11 being spaced from the top 12a of the said plurality of carbon sheets 12 providing a flat tube or longitudinal passage 14 for the reception of a conventional cross-bar

or blade 15 usually employed for use with a manifold-type machine or the like. The said blade or bar 15 is provided with the usual slot 15a for connection with the said machine. Spaced rows of stitches 13 and 16 secure the plurality of carbon sheets 12 and folded sheet 11 together. The folded sheet 11 is perforated as indicated at 17. These perforations may be provided on either one or both sides of the folded sheet. Adheringly disposed over the perforations 17 is an adhesive strip 18 of preferably pressure-sensitive or tacky material. It is apparent that if the blade or cross-bar 15 is inserted in the passage 14 and a slight finger-pressure is then applied to the adhesive strip 18 over the perforations 17, the tacky portions of the strip 18 will occupy space within the perforations and its adhesive surface will adhere to the bar 15, thus fixing the bar and preventing shifting thereof.

Figs. 4 and 5 illustrate the invention as applied to a single sheet 25 having the perforations 26 and the adhesive strip 18 fixed over the perforations.

Figs. 6 and 7 disclose the invention in a modified form, in that the bar 31 is provided with the perforations 32 and the adhesive strip 18 is fixed to the blade or member 31 over the perforation 32.

It is apparent that the sheet 30 may be adhesively secured to the member 31 in a manner heretofore stated as regards the previous figures.

Having thus described the invention, what is claimed as new and desired to be secured by letters patent, is:

1. A carbon paper pack comprising a plurality of sheets, a flexible sheet folded over the top of 35 said plurality of sheets with its fold line spaced

from said top whereby a longitudinal passage is formed, means securing together said plurality of sheets and said flexible sheet along a line spaced from said fold line, at least one perforation in the folded over portion of said flexible sheet communicating with said passage, a strip of flexible material having a pressure sensitive tacky surface adhering to said folded-over portion of said flexible sheet and covering said perforation, said passage being adapted to receive a longitudinal member and a tacky surface of said strip being adapted to adhere to said member through said perforation when said member is inserted in said passage to underlie said perforation.

2. A carbon paper pack according to claim 1 wherein there is at least one perforation on either side of said folded-over portion and a strip of flexible material having a pressure sensitive tacky surface adhering to each side of said folded-over portion over each perforation.

ROBERT A. KOHUT.
